Clayton E. Hyrich
ATTORNEY.

UNITED STATES PATENT OFFICE.

JAMES G. RICHARDS, OF DETROIT, MICHIGAN.

LOADING GANGWAY.

Application filed February 11, 1924. Serial No. 692,061.

This invention relates to a double deck loading gangway for ships and the like and has for its principal object the provision of a gangway which may be raised or lowered to suit the difference in water levels due to tides and other influences.

Another object of the invention is that either the upper or the lower gangway may be operated together or separately.

10 A further object of the invention is to provide an adjustable staircase attached to the upper platform of the loading gangway and supported on rollers at the base, which automatically adjusts itself to the required height 15 of the structure at the same time keeping the steps parallel to the ground.

A still further object of the invention is the provision of a loading gangway constructed to allow the loading and unloading 20 of passengers simultaneously with the loading and unloading of pleasure vehicles, trucks, freight and the like.

These and other objects will be apparent 25 from the following description wherein reference is made to the accompanying drawings illustrating a preferred embodiment of my invention.

In the drawings:

Fig. 1 is a plan view, showing its design 30 and the general layout of the elevating mechanism which is supported on the lower gangway.

Fig. 2 is an elevation showing the adjustable stairway to the upper platform.

35 Fig. 3 is a side elevation showing the gangway leading from the loading platform to the ship's side.

Fig. 4 is a detail showing the elevating mechanism.

40 Fig. 5 is a view of the control, motor and gearing for driving the elevating mechanism.

The upper platform 1 is supported on the lower platform 2 by the tubular columns 3—3, the structure, being securely braced by 45 the rods 3^A—3^A, and constituting the framework of the loading gangway.

Mounted on the upper platform 1 are guard-rail supports 4—4 having attached thereto guard-rails 5—5. The upper platform 50 1 is also provided with a passenger gangway 6 pivotally mounted at 7—7, the outer end of the gangway being supported on the passenger deck 8 of the boat 9. This construction allows the gangway to be raised 55 to a substantially perpendicular position as shown in dotted lines in Figure 3.

The lower platform 2 is also provided with a gangway 10 for loading vehicles, freight and the like. This gangway is pivotally mounted on the lower platform at 60 10^A and is supported at its outer end on the deck 11 of the boat 9, and may be raised to a substantially perpendicular position as shown in dotted line in Figure 3.

Operating means of both gangways will 65 be hereinafter described.

The upper platform is further provided with self-adjusting stairway pivotally mounted at 12—12 and supported on the dock by castors 13—13. This stairway is constructed 70 with steps 14—14 securely attached to the T frames 15—15 and pivotally mounted on the guard-rail 16 and the main support rail 17, so that the steps 14 remain parallel with the ground regardless of the position or incline 75 of the stairway, as shown in dotted lines in Figure 2.

Mounted on the lower platform 2 is a mechanism for raising and lowering the entire structure as described. The power from 80 the motor 18 is transmitted through the clutch 19, thence through gears 20—20 to the shafts 21—21 by bevel gears 22—22.

The shafts 21—21 are provided with worms 23—23 engaging with worm-gears 24—24. 85 The worm-gears 24—24 being rotatably housed in the brackets 25—25 are internally threaded to fit the threads on the screws 26—26. The screws 26—26 are held from rotating by the clamping plates 27—27. 90

It will be noted by the description in the last paragraph that operation of the motor 18 in either direction will cause the complete structure as described to raise or lower 95 its position in relation to the foundation on which it is installed.

Two standard winches 28—28 are provided for raising and lowering the gangways 6 and 10. This is accomplished by the provision of chains 29—29 attached at one end to 100 the gangways, operating over pulleys 30—30 and having their other ends attached to the drums of their respective winches. The levers 31—32—33 are manually operable, allowing the operator to select the operation he 105 may wish the device to perform.

Attached to the lower platform 2, is a runway or tread 34 pivotally mounted at 35, its outer end resting on the dock. This is for allowing egress or ingress to the platform 2 regardless as to whether the structure as described is above or below the dock. 110

While it will be apparent that the illustrated embodiment of my invention herein disclosed is well calculated to adequately fulfill the objects and advantages primarily stated it is to be understood that the invention is susceptible to variation, modification and change within the spirit and scope of the subjoined claims.

Having thus described my invention, I claim:

1. In a device of the character described, the combination with a deck and an adjustable gangway associated with said deck, of mechanism for raising and lowering said deck, mechanism for controlling said gang-

way, a common drive motor for said mechanisms, and means for selectively connecting or disconnecting said motor and mechanisms.

2. In a device of the character described, the combination with a plurality of decks, and gangways pivotally attached to said decks, of separate mechanisms for raising and lowering said decks and said gangways, a motor for actuating said mechanisms and means for independently disconnecting said mechanisms from the motor.

In witness whereof I hereunto set my hand.

JAMES G. RICHARDS.
